[57] CLAIM

The ornamental design for an illuminated house number
display or similar article, as shown and described.

DESCRIPTION

FIG. 1 is a front elevational view of an illuminated
house number display or similar article showing my
new design;

FIG. 2 is a left side elevational view thereof;

FIG. 3 is a right side elevational view thereof;

FIG. 4 is a top plan view thereof;

FIG. 5 is a bottom plan view thereof; and

FIG. 6 is a rear elevational view thereof.

The cross-hatching indicating faceting on the lenses is
partially shown for convenience of illustration, it being
understood that the faceting is continuous over the
lenses. The numerals (shown in broken lines in FIG. 1)
are included for purposes of illustration only and should
not be considered to be part of the design herein.

FIG. 4

FIG. 2
